UNITED STATES PATENT OFFICE.

WILLIAM F. PFEIFFER, OF PITTSBURGH, PENNSYLVANIA.

DESIGN FOR A CANDY-RECEPTACLE.

45,204.

Specification for Design.

Patented Feb. 3, 1914.

Application filed August 2, 1913. Serial No. 782,723. Term of patent 3½ years.

To all whom it may concern:

Be it known that I, WILLIAM F. PFEIFFER, a citizen of the United States, and a resident of Pittsburgh, in the county of Allegheny and State of Pennsylvania, have invented a new, original, and ornamental Design for Candy-Receptacles, of which the following is a specification, reference being had to the accompanying drawing, forming part thereof, in which—

I claim:—

The ornamental design for a candy receptacle, as shown.

WILLIAM F. PFEIFFER.

Witnesses:

J. N. COOKE,
A. D. P. MILLER.
